UNITED STATES PATENT OFFICE.

ROBERT M. BLACKMER, OF MONONGAHELA, PENNSYLVANIA.

ROTARY PUMP.

1,080,676.

Specification of Letters Patent.

Patented Dec. 9, 1913.

Application filed February 11, 1911. Serial No. 607,926.

To all whom it may concern:

Be it known that I, ROBERT M. BLACKMER, a citizen of the United States, residing at Monongahela, county of Washington, State of Pennsylvania, have invented a certain new and useful Improvement in Rotary Pumps, and declare the following to be a full, clear, and exact description of the same, such as will enable others skilled in the art to which it pertains to make and use the same, reference being had to the accompanying drawings, which form a part of this specification.

This invention relates to rotary pumps.

It has for its object an improved pump of rotary bucket carrier class in which there is an improved bucket construction, an improved fluid inlet construction and an improved fluid outlet construction; the fluid enters through an inlet in the side wall, divides and enters the cylinder through the end walls, leaves the cylinder through the end walls and leaves the pump through a passage in the side wall; the bucket carried by a rotary carrier swings in a pocket, carries an oscillating wing member which engages with a minimum of frictional resistance against the carrier and yet serves as an adequate packing member.

In the drawings: Figure 1, is a side elevation of the pump with the end casing removed. Fig. 2, is a perspective of the bucket and packing member. Fig. 3, is a vertical section along line 3—3 of Fig. 1. Fig. 4, is a diagram of the arch curvatures of the cylinder cavity. Fig. 5, is an elevation of the end of the cylinder. Fig. 6, is an (inside) elevation of an end plate of the cylinder.

The main part 1 of the cylinder case is circular in its general outline, is provided with foot plate 1^a, with an inlet 2^a and an outlet 2; the inlet 2^a communicates directly with a chamber 17 in the wall of the casing; the chamber 17 is separated from the cylinder chamber by a diaphragm 23; the edges of the diaphragm engage along the middle line of by pass cavities 24, 25, in the end plates 18, 19. The chamber 16 is separated from the cylinder chamber by a diaphragm 22, the edges of which engage along the middle line of by-pass cavities 20, 21 in the end plates 18, 19; by this construction the arched boundary of the cylinder is unbroken by either inlet or outlet and the bearing edge of the bucket wing 10 wears evenly.

The casing chamber is bounded by four arched surfaces whose curvatures are struck from two centers. The arc from *a* to *b*, which I call the housing arc, has a center 3 and a radius substantially equal to that of the bucket carrier 5. The housing arc extends from substantially a point opposite the end of the intake port 25 to substantially a point opposite the nearer end of the outlet port 21 (Fig. 1). The arched surface *c*, *d*, extends from a point substantially opposite the other end of the intake port 25 to a point substantially opposite the other end of the outlet port 21. This arc I term an extension arc and it is struck from the same center 3 as the housing arc, but with a longer radius. The connecting arcs *a*, *c*, and *b*, *d*, connect these two first mentioned arcs and it is desirable in making such connection that the entire surface of the interior of the chamber should approximate the interior of a cylinder as near as may be possible. It is also a desideratum to have the load thrown upon the buckets gradually and with substantial uniformity. It is also necessary for good results from a pump of this type that the maximum out-throw of the buckets be attained while they are passing the intake port so that the out-throw of the buckets from the end of the intake port to the opposite end of the outlet port is uniform, thereby eliminating any tendency to skip over portions of the surface of the casing and thereby allow leakage and cause loss of efficiency. The approximation of a continuous interior surface of a casing and the elimination, as much as may be, of jutting surfaces to cause wear upon the buckets I have accomplished by the way the connecting arcs are formed. This is by bisecting the housing arc and drawing a line from bisecting point through the center 3 and at a point shortly removed on the farther side on center 3 from the housing arc *a*, *b*, striking arcs which will connect the housing arc *a*, *b*, and the connecting arc *c*, *d*, at points adjacent the ends of the intake and outlet ports.

It is seen from the drawings that the intake and outlet ports are about ninety degrees apart and that the ports 21 and 25, which lead into the ends of the cylinder, each occupy about forty-five degrees of the complete three hundred and sixty degrees of the cylinder. The exact point for locating the figure 4 cannot be stated descrip-

tively, but it may be easily ascertained by trial and is quite definitely shown in the diagram of Fig. 4.

From the above, it is seen that the connecting arcs are struck from a common center and a common radius on the bisecting line of a, b , and from examining the diagram, it is seen that a minimum jutting surface at the juncture of the arcs is afforded, and by reference to Fig. 1, it is seen that the juncture of the arcs are, in each instance, at substantially the end of the ports in the end plates.

The improved results obtained by this structure is a minimum of wear on the buckets, a graduation of the placement and removal of the load from the bucket due to the connecting arcs adjacent the ports, and a uniform out-throw for the buckets from one port end to the other port end due to the extension chamber extending from the end of one port to the opposed end of the other port.

A shaft 35 is mounted to rotate on the center 3 and has secured to it a bucket carrier 5 with a number of pockets; each pocket has a bearing socket 8 in which engages the hub 15 of the bucket; the face of the pocket opposite the socket 8 curves in an arch concentric with the center of the socket and extends from the periphery toward the center of the carrier. The bucket as a whole is a T shaped member made in two parts, one of the arms of the T being pivotally connected to the remainder of the member by a pivot located at the cross; the larger or main part of the member comprises a wing 10 (one arm of the cross) a hub 15 adapted to engage in the socket 8

and arms 9, 9^a which unite the hub to the wing 10; at the turn from the arms 9 to the wing, and on the side opposite the wing is a socket groove 14 which forms a bearing for a hub 11 on the oscillating wing 13, a web extends from the hub and carries a 45 wiping flange 12 adapted to engage closely against the arched surface 6; the opening into the groove 14 is sufficiently wide to allow the wing 13 to swing through a short path and to engage closely against the 50 arched surface 6. The inertia of the water which is struck by the buckets as they sweep along insures a close engagement of the flange 12 against the face 6, which, however, is entirely relaxed as soon as the 55 bucket reaches the discharge and the pressure is equalized on the wing 13.

What I claim is:—

1. In a rotary pump, in combination with a bucket carrier provided with bucket sockets having an arched bearing face, a bucket adapted to swing in said socket and a packing member pivotally connected to said bucket and adapted to swing thereon always in contact with said arched bearing face, 65 substantially as described.

2. In a rotary pump, a bucket carrier provided with a pocket, a bucket provided with a pivot and adapted to oscillate in said pocket, a wing pivotally connected to said bucket, and adapted to bear against a face of said pocket, substantially as described. 70

In testimony whereof, I sign this specification in the presence of two witnesses.

ROBERT M. BLACKMER.
